Patented Nov. 25, 1924.

UNITED STATES PATENT OFFICE.

DAVID GRIMES, OF GRASMERE, NEW YORK.

VACUUM-TUBE AMPLIFIER.

Application filed September 19, 1922. Serial No. 589,108.

To all whom it may concern:

Be it known that I, DAVID GRIMES, a citizen of the United States, and a resident of Grasmere, county of Richmond, and State 5 of New York, have invented certain new and useful Improvements in Vacuum-Tube Amplifiers, of which the following is a specification.

This invention has to do with high frequency signaling systems, and relates, more particularly, to radio and other high frequency receiving, amplifying and repeating systems and circuits therefor.

In so-called vacuum tube "reflex" circuits, 15 particularly high frequency receiving circuits as described in United States Patent No. 1,087,892, issued February 17, 1914, to Schloemilch and Von Bronk, and British Patent No. 132,668, issued to Marius Latour, as well as numerous other patents and publications, the same thermionic vacuum tubes are utilized to effect both radio frequency and audio frequency amplification simultaneously. In the reflex systems comprising a plurality of amplifying tubes heretofore known, the radio frequency amplification and audio frequency amplification were effected by the tubes in corresponding order of sequence. For example, 20 let it be assumed that a reflex receiving circuit of the heretofore known type comprises three vacuum tube amplifiers and a detector. The incoming radio frequency signaling currents are impressed on the amplifier tubes successively in the order 1, 2, 3 and 25 amplified by each tube, after which the amplified high frequency signaling current is impressed on the detector, from which audible frequency current variations corresponding 30 with the signals are derived. The audible frequency currents are then impressed on the same amplifier tubes as before and likewise in the order 1, 2, 3. The amplified audio frequency currents are then 35 impressed on a suitable indicating device such as a loud speaking telephone.

From a consideration of the foregoing it will be seen that the first amplifier tube has impressed upon it both the weakest radio 40 frequency currents and the weakest audio frequency currents, while the third amplifier tube has impressed on it highly amplified radio frequency currents and highly amplified audio frequency currents. It follows that with such an arrangement, the amplifier tubes are most unevenly loaded

and that one tube may be very lightly loaded while another is overloaded. To overcome the aforementioned disadvantage inherent in previous reflex circuits and therefore to increase the efficiency of operation of amplifier tubes, is one of the principal objects of the present invention. 60

A further disadvantage greatly in evidence in previously known reflex circuits employing more than one stage of radio frequency amplification arises from the strong tendency to oscillate at high frequencies. This tendency comes about from the fact that even the most feeble radio frequency 65 oscillations which may be transmitted from the output side of the detector to the input side of the first amplifier tube through the medium of the intervening audio frequency transformer or other audio frequency path 70 are generally so greatly reamplified by the succeeding tubes as to be sustained. This condition is of course likely to result in highly undesirable beat notes and does in fact so result. The elimination of the last-mentioned undesirable condition is a further 75 object of the present invention.

As in the known reflex circuits referred to, the present invention contemplates using the same vacuum tube amplifiers for effecting both radio frequency amplification and audio frequency amplification, but instead of passing the audio frequency currents through the amplifier tubes in the same sequence as the radio frequency currents, thus unevenly loading the tubes, the sequences are reversed, that is to say, the audio frequency amplification is effected by the amplifier tubes in the inverse order or sequence as compared with the order or sequence in which the amplifier tubes are utilized for effecting radio frequency amplification. By comparison with the explanation previously given, it will be seen that a more even loading of the tubes is effected. 80 This results in materially increased efficiency and improved quality of tone reproduction arising from the reduction or elimination of tube distortion. 90

The elimination or reduction of the tendency to sustain high frequency oscillations is accomplished in the circuits of the present invention by reason of the fact that the output of the detector is impressed on the input circuit of the last amplifier tube instead of one of the preceding tubes as heretofore, 100 and accordingly any high frequency oscilla-

tions which may be transmitted from the output of the detector to the input of the last amplifier tube through the medium of the intervening audio frequency path is amplified by only one tube, but it should be borne in mind that the energy of the oscillations under consideration is exceedingly small when impressed on the input of the amplifier tube due to the attenuation of the 5 audio frequency path, and that after a single stage of amplification it is still very small. When these weak oscillations are further attenuated by the succeeding audio frequency path through which they must 10 pass, if they pass at all, their energy is further reduced to such an extent that they are incapable of being built up by the succeeding amplifier tubes to a sufficient extent to result in their being sustained. The 15 fore-going theoretical consideration appears to be consistently borne out by the results which have been obtained in practice. It is thought desirable to point out, however, that the same factors have to be taken into 20 consideration for the prevention of free oscillations as in any vacuum tube circuit arrangement wherein energy may be fed back from the output to the input circuit, namely, that the positive resistance must 25 exceed the negative resistance. In other words, the attenuation of the high frequency oscillatory energy must outweigh the effective amplification. If, then, vacuum tube 30 amplifiers having high amplification factors are employed, the high frequency impedances of the audio frequency paths (this refers more particularly to the mutual capacities between the windings of the audio 35 frequency transformers—which capacities 30 must be correspondingly low for high impedance to radio frequencies) must be correspondingly high, but if the amplification factor is low, the high frequency impedances may be correspondingly low. Since 40 the vacuum tube amplifiers to be employed are usually decided upon in advance, the controllable factor in the design resides in the audio frequency path. The desired high frequency impedance, or, more specifically, 45 low mutual capacity between windings, may be and generally is obtainable by proper design of the audio frequency transformers without any ancillary apparatus for increasing the high frequency impedance being 50 provided.

For the purpose of distinguishing circuit arrangements according to the present invention, the term "inverse duplex" has been coined and adopted. As may easily be implied, this term refers to circuits wherein some or all of the amplifier tubes are utilized for both radio frequency and audio frequency amplification (thus "duplex") and that the tubes are effective in the inverse 55 order as already explained. The term "in-

verse duplex" therefore has a definite meaning which it is desired be scrupulously observed.

In the following detailed description of one of the preferred embodiments of the 70 invention additional novel features and objects will be pointed out.

The drawing shows a circuit diagram of an "inverse duplex" receiver and amplifier comprising three amplifier tubes 1, 2 and 3 75 and detector tube 4. Each of the tubes is of the three electrode type, including filament, plate and grid, or, in other terminology, cathode, anode and control electrode respectively. It is not at all essential that 80 the detector should be of the vacuum tube type. Excellent results are obtainable with other types of detectors including crystal detectors. In the present example all the amplifier tubes are utilized for both radio 85 frequency amplification and audio frequency amplification, but the invention is not limited to this arrangement, nor is it limited to the number of amplifier tubes employed except that there must be at least two stages 90 of radio frequency amplification and two stages of audio frequency amplification. In some cases it may be desirable to have only two stages of audio frequency amplification and three stages of radio frequency, in 95 which event any two of the amplifier tubes may be utilized for audio frequency amplification. A number of other arrangements may also be resorted to depending upon the total number of amplifier tubes 100 and the amount of radio frequency and audio frequency amplification desired.

Conductors 17, 18 may extend to a radio receiving system such as antenna and ground respectively or to the terminals of a loop 105 or they may connect with a metallic transmission line as in the case of so-called carrier current or wired radio telephone systems.

Variable condenser 16 is provided for 110 tuning purposes, and is used, more particularly, when the apparatus is provided with a loop antenna, which for the present purposes it will be assumed is employed.

The incoming high frequency signaling 115 currents supplied by the loop are conducted through the medium of condenser 29 and conductor 57 to the grid 38 and filament 46. Condenser 29 is designed to pass the high frequency currents while substantially 120 blocking audio frequency current. The weak high frequency current being amplified in the usual way in tube 1 appears in amplified form in the high frequency output circuit of tube 1, which includes plate 125 39, primary winding 50 of radio frequency transformer 5, condenser 28 and filament 46. Condenser 28 is generally of low capacity, providing a by-pass for high frequencies, but very high impedance for low 130

5 frequencies. The adjacent input and output sides of succeeding tubes are interconnected through the medium of high frequency transformers 5, 6 and 7, each of which is designed to pass high frequency currents but to provide no path, or at most a very inefficient path for audio frequency currents. Condensers 23, 24, 25, 26 and 27 which are provided as by-passes for 10 the high frequency currents are of such proportions as to greatly impede the passage of audio frequency currents. The high frequency currents are repeatedly amplified by the amplifier tubes in the order 15 1, 2, 3 and finally pass through the medium of transformer 7 to detector tube 4. The input circuit of the detector tube includes a grid condenser and leak 37, the function of which is well known.

20 The detector tube converts the super-audible high frequency energy into audible frequency currents in the usual manner. The output circuit of the detector tube includes plate 45, filament 49, battery 13 and primary winding 35 of the audio frequency transformer 10. As previously stated, condenser 23 functions to by-pass any high frequency currents which may appear in the output of the detector, thus greatly reducing 25 the energy of any high frequency current output which might be conducted to the primary winding 35 of transformer 10.

Amplifier tube 3, being the last in the 30 series of radio frequency amplification steps, and therefore most heavily loaded at radio frequency, is utilized for the first audio frequency amplification step. Secondary winding 34 of transformer 10 is accordingly connected to the input circuit of 35 tube 3 in series with the secondary winding 53 of radio frequency transformer 6, conductor 59 and grid 42. The other end of secondary winding 34 is connected to filament 48 through contact 36 of potentiometer 15. The audio frequency current is therefore impressed across the grid 42 and filament 48 and is amplified by tube 3. The output circuit of amplifier tube 3 in tubes 43, primary winding 54 of the radio 40 frequency transformer 7, primary winding 33 of the audio frequency transformer 9, batteries 13, 14 and filament 48 all in series.

Secondary winding 32 of transformer 9 is 45 connected with the input circuit of the amplifier tube in the same manner as the secondary winding 34 of transformer 10 is connected with the input circuit of amplifier tube 3.

The audio frequency input circuit of 50 amplifier tube 2 includes grid 40, conductor 58, secondary winding 51 of radio frequency transformer 5, secondary winding 32 of audio frequency transformer 9, contact 36 of potentiometer 15 and filament 47.

55 The transference of amplified audio fre-

quency current from the output of amplifier tube 2 to the input of amplifier tube 1 is effected, as in the preceding instances, through the medium of audio frequency transformer 8 which includes a primary 70 winding 31 connected in the output circuit of amplifier tube 2 and secondary winding 30 connected in the input circuit of amplifier tube 1. The secondary winding 30 is preferably, but not necessarily, 75 connected, as shown, to one side of the filament 46 through conductor 61. A direct connection between secondary winding 30 and grid 38 of amplifier tube 1 may be effected through the loop which would ordinarily be connected to the terminals of conductors 17 and 18. In the event of the apparatus being used in conjunction with an ordinary antenna or a metallic transmission line, the secondary coil of a variacoupler 80 may be connected across the terminals with the conductors 17 and 18, thus providing a path for the audio frequency currents in the input circuit of amplifier tube 1.

The audio frequency output circuit of 85 amplifier tube 1 includes the plate 39, primary winding 50 of radio frequency transformer 5, a suitable indicating device 11 such as a loud speaking telephone, batteries 13 and 14 and filament 46.

The iron cores of transformers 8, 9 and 90 10 are preferably grounded to the output filaments as indicated, for instance, by conductor 62.

Filament resistances 19, 20 and 21 may be 95 fixed as indicated, and their value is determined by the filament current requirements and the voltage of the filament lighting battery 12. Resistance 22 is preferably variable on account of being associated with the 100 detector tube 4, which is more critical on filament temperature than are the amplifier tubes.

Since amplifier tube 1 effects the least 105 radio frequency amplification and, contra, the largest audio frequency amplification, and since the reverse is true of amplifier tube 3, it is evident that the load on these two tubes tends to approach equality. The same is apparently true with respect to amplifier tube 2, since the radio frequency and audio frequency loads, respectively, are intermediate those carried by tubes 1 and 3.

By reason of this novel arrangement, it is found that the amplifier tubes may be operated with increased efficiency and that the quality of the output is materially improved. It has been explained in a preceding paragraph how the circuit arrangement under consideration is effective to suppress the formation of high frequency sustained oscillations, but a further explanation in connection with the circuit diagram is thought to be not out of order. Any high frequency feedback from the output of de- 110 115 120 125 130

tector tube 4 which may reach the input of amplifier tube 3 must pass through transformer 10. Any high frequency leakage of this character is amplified by tube 3 and 5 returned, in part, to the input of detector tube 4 through transformer 7, and, in part, to transformer 9, from which it may be conveyed to the input of tube 2, and, in turn, through transformer 8 to the input of tube 10. 1. Since the attenuation at high frequencies of transformers 8, 9 and 10 is very high, the high frequency currents which may be fed back therethrough are accordingly very weak. If the attenuation of 15 transformer 10 due to the low mutual capacity between the windings more than offsets the effective amplification of tubes 3 and 4, the high frequency oscillations under consideration cannot be sustained by tubes 20 3 and 4 alone. But it is necessary to take into consideration the possibility of some of the high frequency current leakage finding its way back as far as the input of tube 1, and that, such being the case, all the tubes 25 are available for re-amplification. In a circuit comprising several tubes, the amplification and attenuation of high frequency leakage presents quite a complex situation which is not easily calculated with accuracy, but the 30 fact remains that if the effective attenuation of the audio frequency paths to the high frequency oscillations is sufficient to more than offset all the effective amplification available to such high frequency leakage as 35 may exist, there can be no sustained oscillations set up. It is, therefore, essential to the best practice that the transformers 8, 9 and 10 be designed to provide sufficient attenuation at high frequencies (i. e., that 40 the mutual capacity between windings be sufficiently low) or that some provision be made externally of the audio frequency transformer for obtaining the necessary attenuation.

45 A further comparative advantage in the present system over the heretofore known "reflex" circuits arises from the fact that the telephone 11 is connected to the output of the amplifier tube immediately adjacent the loop. This provides only one stage of amplification for any audio frequency disturbing currents which may reach the loop, such, for example, as the 60 cycle current of neighboring electric light lines. It has 50 been found that a single stage of amplification is usually insufficient to increase the intensity of low frequency disturbances to a point where they become materially noticeable, whereas with two or three stages of 55 amplification, such disturbances may be of such strength as to practically obliterate the signals.

60 Although the explanation herein contained concerning the theory of operation 65 of the system described are believed to be

correct, the invention is in no way dependent upon an accurate understanding of the theory and should not be construed as limited by such considerations. Neither is it essential to the invention that the elements 70 of the circuit be designed to prevent sustained oscillations, although that is generally the preferred practice.

Having thus described my invention, what I claim and desire to secure by Letters Patent is—

1. A system comprising a plurality of amplifiers arranged for interstage operation, and circuit connections for said amplifiers, said circuit connections being so arranged 80 that said amplifiers are operable to amplify current variations of two different bands of frequencies, and means including said circuit connections whereby the current variations within one band of frequencies are impressed upon the amplifiers in a predetermined order, and the current variations within the other band of frequencies are impressed upon the amplifiers in the inverse order as compared with the aforementioned 90 predetermined order.

2. A multi-stage amplification system comprising a plurality of amplifiers, circuit connections for said amplifiers, the arrangement being such that superaudible high frequency current variations are repeatedly amplified by said amplifiers in a predetermined order, and means whereby a plurality of said amplifiers are rendered operable to repeatedly amplify audible frequency current variations in the inverse order as compared with the aforementioned predetermined order.

3. A multi-stage amplification system comprising a plurality of amplifiers, circuit connections for said amplifiers, the arrangement being such that modulated super-audible high frequency current variations are repeatedly amplified by said amplifiers in a predetermined order, means for rectifying the amplified output of said amplification system whereby audible frequency current variations are derived, and means whereby a plurality of said amplifiers are rendered operable to repeatedly amplify the audible 110 frequency current variations from said rectifying means in the inverse order as compared with the aforementioned predetermined order.

4. A multi-stage amplification system 120 comprising a plurality of thermionic amplifiers arranged to repeatedly amplify modulated super-audible high frequency current variations in a predetermined order, means interconnecting said amplifiers operable to transmit super-audible high frequency currents with relatively high efficiency but inoperable to transmit audible frequency currents to an appreciable extent, means for rectifying the amplified super- 130

audible high frequency output of said amplification system whereby audible frequency current variations are derived, and means whereby a plurality of said amplifiers are rendered operable to repeatedly amplify the audible frequency current variations from said rectifying means in the inverse order as compared with the aforementioned predetermined order, said last-mentioned means being operable to transmit audible frequency current variations with relatively high efficiency, but inoperable to transmit super-audible high frequency current variations to an appreciable extent.

5 15. A multi-stage amplification system comprising a plurality of thermionic amplifiers and circuit connections for said amplifiers, said circuit connections being so arranged that said amplifiers are operable 20 to repeatedly amplify current variations of two different bands of frequencies, and means including said circuit connections whereby the current variations within one band of frequencies are impressed upon the 25 amplifiers in a predetermined order, and the current variations within the other band of frequencies are impressed upon the amplifiers in the inverse order as compared with the aforementioned predetermined order.

30 16. A multi-stage amplification system comprising a plurality of thermionic amplifiers having input and output circuits and arranged to repeatedly amplify super-audible high frequency current variations in a 35 predetermined order, one or more transformers operable to pass super-audible high frequency currents with relatively high efficiency but inoperable to pass audible frequency currents to an appreciable extent, 40 succeeding ones of said amplifiers being inter-connected in each instance through the medium of one of said transformers, means for rectifying the amplified super-audible high frequency currents and thereby obtaining audible frequency current variations, 45 means operable to transmit the audible frequency currents from said rectifying means to the input circuit of one of said amplifiers wherein the audible frequency current variations are amplified, and means operable to 50 transmit the amplified audible frequency current from the output circuit of said last-mentioned amplifier to the input circuit of another of said amplifiers wherein further audible frequency amplification is effected, 55 said two last-mentioned amplifiers being operable to amplify audible frequency current variations in the inverse order as compared with the order in which they are operable to 60 amplify super-audible high frequency current variations.

65 7. In a signaling system, two thermionic amplifiers in cascade relation, input and output circuits for said amplifiers, a radio frequency transformer having its primary

winding connected in the output circuit of the first of said amplifiers and its secondary winding in the input circuit of the second of said amplifiers, a second radio frequency transformer having its primary winding in 70 the output circuit of said second amplifier, a rectifier, the secondary winding of said second transformer being connected in circuit with the said rectifier, an audio frequency transformer having its primary winding connected with said rectifier, the secondary winding of said audio frequency transformer being connected in the input circuit of said second amplifier whereby low 75 frequency current variations derived from said rectifier are impressed upon the input circuit of said second amplifier wherein they are amplified, a second audio frequency transformer having its primary winding connected in the output circuit of said second amplifier and its secondary winding in 80 the input circuit of said first amplifier whereby the audible frequency current variations are further amplified by said first amplifier.

8. A system comprising a plurality of vacuum tube amplifiers each including a cathode, an anode and a control electrode, circuit connections for said amplifiers, said amplifiers and circuit connections being arranged for interstage operation, and means including said circuit connections whereby certain of said amplifiers are rendered operable to amplify electrical current variations of a plurality of frequencies simultaneously, the arrangement being such that current variations within one band of frequencies are amplified by said amplifiers in a predetermined order, and current variations within a different band of frequencies are amplified by at least two of said amplifiers in the inverse order to that in which said last mentioned amplifiers amplify current variations within said first mentioned band of frequencies.

9. A multi-stage amplification system comprising a plurality of amplifiers, circuit connections for said amplifiers, the arrangement being such that super-audible high frequency current variations are repeatedly amplified by said amplifiers in a predetermined order, and means whereby a plurality of said amplifiers are rendered operable to repeatedly amplify audible frequency current variations in the inverse order as compared with the aforementioned predetermined order, both the super-audible and audible frequency current variations being amplified simultaneously.

10. A multi-stage amplification system comprising a plurality of three-electrode vacuum tube amplifiers arranged to repeatedly amplify modulated super-audible high frequency current variations in a predetermined order, means, interconnecting said

6
amplifiers, operable at relatively high efficiency to transmit super-audible high frequency currents but at low efficiency to transmit audible frequency currents, a three-electrode vacuum tube detector having its input electrodes connected to the output end of said amplification system, and means whereby a plurality of said amplifiers are rendered operable to repeatedly amplify the audible frequency current variations from said detector in the inverse order as compared with the aforementioned predetermined order, said last-mentioned means being operable at relatively high efficiency to transmit super-audible high frequency currents.

11. The method of amplification which consists in impressing high frequency signaling currents on a plurality of amplifiers in seriatim and effecting further amplification in each successive step and simultaneously impressing low frequency signaling currents on the same amplifiers in seriatim but in the inverse order and effecting further amplification in each successive step.

25 12. The method of signal reception and

amplification which consists in impressing modulated high frequency signaling current on a plurality of amplifiers in seriatim and effecting further amplification in each successive step, converting the amplified high frequency signaling current into audible frequency signaling current, impressing the audible frequency signaling current on the same amplifiers in seriatim but in the inverse order and effecting further amplification of the audible frequency currents in each successive step. 30 35

13. The method of utilizing vacuum tubes as amplifiers, which consists in utilizing the tubes in a predetermined sequence for repeatedly amplifying high frequency variations, rectifying the amplified high frequency variations thereby obtaining lower frequency variations, and subsequently utilizing the same tubes in inverse sequence for 40 45 repeatedly amplifying the lower frequency variations.

In witness whereof, I have hereunto set my hand this 18 day of September, 1922.

DAVID GRIMES
